CLAIM

The ornamental design for a foam container, substantially as shown and described.

DESCRIPTION

FIG. 1 is a top perspective view of a foam container, showing our new design;

FIG. 2 is a top view thereof;

FIG. 3 is a bottom view thereof;

FIG. 4 is a left side view thereof;

FIG. 5 is a right side view thereof;

FIG. 6 is an end view thereof; and,

FIG. 7 is an end view thereof, opposite FIG. 6.

(Continued)

The stipple shading is fragmentarily shown, it being understood that the stipple shading is uniformly continuous across the surface of the container.

1 Claim, 3 Drawing Sheets
